UNITED STATES PATENT OFFICE.

FREDERICK SAYLES, OF LONGMONT, COLORADO.

DISINFECTANT-HOLDER.

1,163,267.

Specification of Letters Patent. Patented Dec. 7, 1915.

Application filed May 29, 1915. Serial No. 31,247.

To all whom it may concern:

Be it known that I, FREDERICK SAYLES, a citizen of the United States, residing at Longmont, in the county of Boulder and State of Colorado, have invented certain new and useful Improvements in Disinfectant-Holders, of which the following is a specification, reference being had to the accompanying drawings.

10 This invention relates to an improved disinfectant holder for the mouth piece of a telephone, and has for its primary object to provide a device of this character which may be readily applied to the mouth piece 15 of the ordinary telephone without necessitating any changes whatever in the construction thereof or requiring resort to the services of an electrician or mechanic.

15 It is another object of the invention to 20 provide a disinfectant holder having means for furnishing a continuous supply of disinfecting or sterilizing vapor to the interior of the mouth piece, thus obviating the transmission of disease in the use of the 25 telephone by the general public.

The invention has for another general object to improve and simplify the construction of devices of the above character, whereby the same may be produced at a 30 minimum manufacturing cost and readily obtained and applied by the individual subscriber.

With the above and other objects in view, my invention consists in the novel features 35 of construction, combination, and arrangement of parts to be hereinafter more fully described, claimed, and illustrated in the accompanying drawing, in which,

Figure 1 is a perspective view showing my 40 improved disinfectant holder applied to the transmitter of a telephone; and Fig. 2 is a vertical section.

Referring in detail to the drawing, 5 designates the body of the holder which may 45 be of cylindrical or polygonal form and preferably consists of two sections which are hermetically sealed together or otherwise permanently connected.

In the manufacture of the device, raw 50 cotton or other material having high absorbent qualities, indicated at 6, is placed within the holder and the body of the holder is provided upon its peripheral wall with an outwardly projecting nipple 7 through 55 which a liquid disinfectant may be poured upon the cotton or other absorbent. A suit-

able cap 8 is provided whereby this nipple may be closed.

To the back wall of the holder, a radially projecting hanger arm 9 is soldered or 60 otherwise permanently fixed, said arm being formed with an opening, indicated at 10, for engagement upon the threaded neck portion of the transmitter mouth piece, shown at T. Thus, it will be apparent that, 65 when the mouth piece is threaded upon the body of the transmitter, the end of the hanger arm is tightly clamped in place so that the holder is supported in a pendant position.

To the body of the holder 5, adjacent to its periphery and preferably at the upper portion thereof immediately beneath the mouth piece T, one end of the tube 12 is secured, said tube projecting outwardly and 70 being bent or returned upon itself and having an upwardly inclined end portion 14, the open end of the tube being disposed contiguous to the perforated inner end wall of the transmitter mouth piece.

In the operation of the device, after attaching the holder in the manner above described, it will be apparent that the disinfectant vapor with which the absorbent material contained in the holder is saturated, 85 will escape from the open end of the tube 12 into the transmitter mouth piece, and thus kill or destroy any disease germs which may have collected therein. It will, therefore, be seen that I have produced a very 90 simple and effective device which will minimize liability of the transmission of disease from the use of telephones by the general public.

The device may be maintained in effective 95 condition by supplying the disinfectant to the container or holder at intervals of three or four months. It is, of course, apparent that the holder may be made of any desired size or capacity and that two or more vapor 100 tubes can also be provided, if desired.

The device, as a whole, is exceedingly simple in its construction, highly serviceable and convenient in practical use, and can be retailed at a low price so that the 105 device may be obtained and applied by the individual subscriber.

While I have shown and described the preferred construction and arrangement of the several parts of the device, it is to be 110 understood that the same is susceptible of considerable modification therein, and I,

therefore, reserve the privilege of resorting to all such legitimate changes as may be fairly embodied within the spirit and scope of the invention as claimed.

5 Having thus fully described my invention, what I desire to claim and secure by Letters Patent is:—

The combination with a telephone transmitter having a removable threaded mouth piece, of a disinfectant holder adapted to contain an absorbent material and provided with a nipple through which disinfectant may be supplied to said material, a closure cap for the nipple, a hanger fixed to the 10 holder body and adapted to be engaged 15

upon the transmitter mouth piece and clamped thereby against the body of the transmitter, and a tube fixed to the holder body at one of its ends extending outwardly beneath the mouth piece and being then returned upon itself and obliquely extended upwardly into the mouth piece to supply disinfectant vapor to the mouth piece adjacent to the transmitter diaphragm. 20

In testimony whereof I hereunto affix my 25 signature in the presence of two witnesses.

FREDERICK SAYLES.
